BY ATTORNEY

UNITED STATES PATENT OFFICE

HEINRICH BANGERT, OF DUSSELDORF, GERMANY

METAL-BAR-HEATING FURNACE

Application filed February 11, 1928, Serial No. 253,650, and in Germany February 28, 1927.

My invention relates to improvements in furnaces for heating metal bars and more particularly in furnaces of that type in which bars are gradually advanced through the furnaces by means of a plunger from the intake end of the furnace and through the same, the pressure of the plunger being transmitted from one bar to the other. When thus heating bars of small diameter the said bars are liable to be pushed one above the other, so that a proper operation of the furnace is impossible. In such cases it is necessary to advance the bars by hand. Further, the bars moving through the furnace are in contact with one another, so that they are not uniformly heated, and it is necessary to leave the same within the furnace for a long time for uniformly heating the same.

The object of the improvements is to provide a means by which the bars are passed through the furnace in the proper relative positions, and so that the flame has access to the sides thereof, and with this object in view my invention consists in placing the bars on suitable supports adapted to be pushed by the plunger through the furnace, successive supports being in engagement with one another so that the pressure of the plunger is transmitted from one support to the other, and the supports being guided so that they are held in the proper positions.

In carrying out my invention I provide guide ways longitudinally of the furnace, and I place on the said guide ways supporting rods adapted to slide in said guide ways and engaging one another with their end faces, the bars being placed on the said supporting rods transversely of the guide ways and at suitable distances apart. Thus the pressure of the plunger is transmitted through the supporting rods, and it does not act on the bars to be heated which are therefore held in the proper positions.

For the purpose of explaining the invention a furnace and various methods of supporting the bars have been illustrated in the accompanying drawings in which the same letters of reference have been used in all the views to indicate corresponding parts. In 50 said drawings,

Fig. 1 is a sectional elevation of the furnace,

Fig. 2 is a sectional elevation taken on the line 2—2 of Fig. 1,

Fig. 3 is a sectional elevation similar to 55 the one shown in Fig. 1 and illustrating a modification,

Fig. 4 is a sectional elevation taken on the line 4—4 of Fig. 3, and

Fig. 5 is a partial plan view partly in section and taken on the line 5—5 of Fig. 3 and showing a modification of placing the bars on their supports.

Referring now to the example illustrated in Figs. 1 and 2, the general construction of the furnace is known in the art and I deem it not necessary to describe the same in detail. On the floor of the furnace two guide ways are provided which as shown are in the form of rails *a* formed in their top surface with 60 guide channels or recesses. Below the said rails pipes *4* are embedded in the brick work of the furnace, and the said pipes are connected with a supply of cooling water. The channel or recess of each rail *a* is adapted to receive a series of short supporting rods *c*, and the successive rods of each series are in engagement with one another at their ends. The rods are adapted to be advanced by means 65 of a reciprocating plunger *d*. In front of the intake end *e* of the furnace there is a table *f* which is adapted to have pairs of supporting rods *c* and a bar or a bundle of bars *b* placed thereon.

In carrying out my invention I combine a suitable number of bars into a bundle *b*, the bars being held together by thin wires wound around the ends of the bundle. I place a pair of supporting rods *c* on the table *f*, and I place the bundle *b* on the said rods. Thereafter the plunger *d* is advanced for pushing the supporting rods *c* and the bundle *b* carried thereby into the furnace. The rods *c* will now engage with their end faces the end faces of the supporting rods *c* which before 95 have been pushed into the furnace, and the power of the plunger is thus transmitted through the supporting rods *c* to all the pairs of supporting rods which have before been pushed into the furnace with bundles *b* 100

placed thereon. It appears therefore that the pressure of the plunger *d* does not act on the bundles *b*, and that therefore the bundles remain in the proper relative positions. Further, the bundles are spaced from each other so that the heating gas has access to the sides of the bundles and to the bottoms thereof. As the series of supporting rods *c* are advanced through the furnace, they successively reach the hearth *g*. The rods are removed from the said hearth, and they are carried to the intake end of the furnace for repeated use. By circulating cooling water through the pipes 4 the rails *a* and the rod *c* are kept cool.

As shown, the floor of the furnace is preferably provided with upstanding kerbs or ribs *a'* providing a gutter receiving the skid rails *a* having in their upper faces the guide channels in which the supporting rods *c* slide. The opposed faces of the skid rails and surface of the floor of the furnace in the gutters are recessed to provide conduits to receive the cooling pipes 4. By this construction all the parts are adapted to be securely retained in position, while made removable for ready renewal or repairs when required, and at the same time not only the cooling pipes, but also the channeled rails, are relieved from undue wear, as the rails only are subjected to the wear of the narrow rods *c* thereon.

In Figs. 3 and 4 I have illustrated a modification of the invention. The construction of the furnace is the same as that described with reference to Figs. 1 and 2. Instead of arranging the bars into the form of bundle stacks before pushing the same into the furnace, I place a plurality of bars *h* one beside the other on a pair of supporting rods *c*, thereafter I place a pair of supporting rods *c'* on the bars *h*, and I place a second layer of bars *h* on the rods *c'*, and so on, so that a layer stack of bars is formed. Figs. 3 and 4 showing a stack composed of three layers of bars *h*. The supports *c* and bars *h* are pushed through the furnace in the same way as has been described with reference to Figs. 1 and 2. By disposing all the bars suitable distances apart welding of the said bars is prevented, and the flame has access to all the bars individually, so that the efficiency of the furnace is high.

In the modification shown in Fig. 5 the bars *h* are angularly placed on their supports and so that successive layers of bars *h* cross one another. When thus placing the bars one upon the other the intermediate rods *c'* may be dispensed with.

In the practice of the invention I have found that the efficiency of the furnace is high, that the consumption of fuel is reduced, and that the operation is very reliable.

I claim:

1. In a continuous furnace for heating bars, an elongated heating chamber formed

with a hearth and having an intake end remote from said hearth, skid bars on the bottom of said chamber and extending from the intake end to the hearth, said bars having shallow guide channels in their upper faces, and billet supporting rods guided on said channels and projecting above the same to form supports, for the billets, and means for pushing said rods through said furnace.

2. A furnace for heating billets comprising an elongated heating chamber formed with a hearth and having an intake end at a distance from said hearth, skid bars on the bottom of said chamber and extending from the intake end to the hearth, said bars having their top faces provided with shallow channels, supporting rods guided in said channels of the bars for supporting the billets to be heated, means for pushing said rods through the channels, the opposed faces of the chamber bottom and the bars being recessed to provide channels, and cooling pipes beneath said bars and enclosed in said channels.

3. A furnace for heating billets comprising an elongated heating chamber formed with a hearth and having an intake end away from said hearth, the floor of said chamber being provided with upstanding parallel ribs, stationary skid bars mounted between said ribs and held from displacement thereby and provided with shallow channels in their upper faces, supporting rods guided in said channels for supporting the billets to be heated, means for pushing said rods through the furnace, the opposed faces of the skid bars and floor of the furnace being recessed to provide channels, and cooling pipes enclosed in said channels and underlying the skid bars.

In testimony whereof I affix my signature.

HEINRICH BANGERT.
